UNITED STATES PATENT OFFICE

WILLIAM E. WHITE, OF CHICAGO, ILLINOIS, ASSIGNOR TO KALMAN STEEL COMPANY, OF CHICAGO, ILLINOIS, A CORPORATION OF DELAWARE

METHOD OF BRIDGING

Application filed December 5, 1928. Serial No. 323,897.

My invention relates to buildings, and particularly to a method of installing bridging between joists and beams.

An object of my invention is to provide a simple and expeditious method of installing bridging members to produce a resulting structure that will resist both compression and tension stresses. This has a structural advantage that is not possessed by the forms 10 of bridging at present in use, consisting of wire lacing.

The method will be more readily understood by reference to the accompanying drawings, in which—

15 Fig. 1 is a view of a tension wire such as used by me;

Fig. 2 is a perspective view of one of the attaching hooks;

20 Fig. 3 is a perspective view of the compression strut;

Fig. 4 is a perspective view of the parts following the first steps of installation;

Fig. 5 is a view following a successive step;

25 Fig. 6 is an enlarged elevation with the beams in section, showing the completed structure;

Fig. 7 is a perspective view of the complete finished structure;

30 Fig. 8 is a side elevation thereof; and

Fig. 9 is a plan view.

At the beginning of the operation it is assumed that the beams or joists A—B which are part of a series, are placed in approximately their correct spaced relation. To assist in placing the beams, I may use a temporary wood spacer 10 indicated in dotted lines in Fig. 4. The parts of my bridging consist of a length 11 of flexible wire preferably having a rebent portion 12 constituting a hook; a hook member shown in Fig. 2 consisting of a length of wire bent into U-shape, the legs 13 of which have their ends 14 rebent to form hooks, and a compression strut 15 of channel shape having notches 16 formed in the web of the channel at its ends.

45 With the joists in the position shown, one of the hooks shown in Fig. 2 is engaged with the hook end of the wire 11 and caused to engage the bottom flange of the joist B. The

wire extends upwardly and lies on top of the top flange of the joist A and a second hook member is placed in the position shown. At that point, the strut 15 is placed in the position shown in Fig. 5, that is, with the notch in the lower end engaging the bottom flange of the joist B closely adjacent to the tension wire, and the upper end, engaging the top flange of the joist A in a position about 2½ inches from the tension wire. The upper free end of the tension wire is then bent backward with a sharp pull by the operator, thus pulling the joists into engagement with the ends of the strut in its inclined position, the end of the wire being thereafter bent downward to fix the parts. The strut is, by blows of a hammer or otherwise then forced into a position parallel with the tension wire. This serves to spread the joists to their predetermined spacing, and to place the tension member under considerable stress. When the parts have reached the final position, the free ends, 12, 17 of the tension wire may be bent around the strut to firmly connect the same. The final structure is shown in Figs. 7, 8 and 9 from which it will be evident that the bridging may be installed in alignment through the width of a floor. The structure is permanent, places the joists in a fixed position as to both compression and tension stresses and may be very quickly and simply applied.

It will be understood, that where trusses are used, in place of solid beams, the tension member may consist of a length of wire that passes completely around the respective flanges and has its ends twisted. Also, that other forms of the strut may be adopted together with modifications in the method of applying the same, all without departure from the spirit of my invention.

I claim:

1. The method of installing bridging between beams, which consists in placing a rigid strut between adjacent beams in an inclined position relative to a transverse line between the beams, then connecting a tension member to the beam flanges and pulling the beams toward each other as far as permitted by the strut, and then driving the strut into paral-

lelism with the tension member to spread the beams and thereby place the tension member under greater tension.

2. The method of bridging joists which 5 consists in placing a compression strut in contact with the flanges of adjacent joists in an inclined position relative to its final position, then connecting a tension member between said flange and placing the same under 10 tension, and then forcing the strut into a position parallel with the tension member and thereby placing the tension member under greater tension.

3. The method of bridging joists which 15 consists in placing a compression strut in contact with the flanges of adjacent joists in an inclined position relative to its final position, then connecting a tension member between said flanges and placing the same under 20 tension, then forcing the strut into a position parallel with the tension member and thereby placing the tension member under greater tension, and then bending a free end of the tension member around the strut to connect 25 the same.

4. The method of bridging joists which 30 consists in placing a compression strut in contact with the flanges of adjacent joists in an inclined position relative to its final 35 position then connecting a flexible tension member to the upper and lower flanges respectively of adjacent joists and manually pulling the same up tightly and twisting an end to fix the same, and then forcing the strut into final position to fix the spacing of the flanges and to place the tension member under greater tension.

5. The method of bridging joists which 40 consists in placing a compression strut in contact with the flanges of adjacent joists in an inclined position relative to its final position then connecting a flexible tension member to the upper and lower flanges respectively of adjacent joists and manually pulling the 45 same up tightly and twisting an end to fix the same, then forcing the strut into final position to fix the spacing of the flanges and to place the tension member under greater tension, and then bending an end of the tension member around the strut.

6. The method of bridging joists which 50 consist in placing between the joists a spacer that will permit the joists to occupy a position more closely adjacent than the predetermined 55 final position, then connecting a tension member between the respective flanges of the joists and pulling the joists as close together as permitted by said spacer, and then driving a compression strut between the joists to separate 60 the same to a predetermined spacing and to place the tension member under greater tension.

7. The method of bridging joists which 65 consists in placing between the joists a spacer that will permit the joists to occupy a posi-

tion more closely adjacent than the predetermined final position then connecting a tension member between the respective flanges of the joists and pulling the joists as close together as permitted by said spacer, then driving a compression strut between the joists to separate the same to a predetermined spacing and to place the tension member under greater tension, and then connecting the tension member and strut.

In testimony whereof I have affixed my signature.

WILLIAM E. WHITE.
